PUMP.

1,420,052.

Specification of Letters Patent. Patented June 20, 1922.

Application filed August 18, 1919. Serial No. 318,244.

To all whom it may concern:

Be it known that I, JAMES P. MONTGOMERY, a citizen of the United States, residing at Moore, in the county of Cleveland 5 and State of Oklahoma, have invented a new and useful Pump, of which the following is a specification.

This invention has reference to pumps particularly to deep well pumps for pumping either oil or water, and its object is to provide a balanced pump in which the force necessary to do the pumping is greatly diminished.

In accordance with the invention two reciprocating cylinders are provided and are each carried by a pipe constituting a pump rod serving to reciprocate the cylinder and at the same time conduct the pumped liquid. Each cylinder is entered by a pipe along 15 which the cylinder moves axially and this pipe is furnished with a check valve at the upper end. The pipe constitutes a stationary displacement piston and the water to be pumped enters the cylinder through such 20 displacement piston. The upper end or head of each cylinder also is provided with a check valve. Both check valves open upwardly. The area of the lower head of the cylinder within the cylinder is such as to exceed the area of the outlet at the upper end 25 of the cylinder.

The invention will be best understood from a consideration of the following detailed description taken in connection with 30 the accompanying drawing forming part of this specification, with the understanding, however, that the invention is not confined to any strict conformity with the showing of the drawing, but may be changed and modified so long as such changes and modifications mark no material departure from the salient features of the invention as expressed in the appended claims.

In the drawings:—

Figure 1 is an elevation, with some parts in section, of a pump installation embodying the invention, the well being of the deep well type.

Figure 2 is a longitudinal central section 50 through the cylinder assembly, higher portions of the installation being omitted and the figure being on a larger scale than Figure 1.

Referring to the drawing, there is shown 55 a well casing 1 which may be taken as in-

dicative of any suitable well structure, but particularly a deep well. It is customary to provide deep wells with a tower 2 which may be utilized in connection with the pump structure of the invention.

The pump comprises two cylinders 3, 4 respectively, the cylinder 3 being carried by a pipe 5 and the cylinder 4 by a pipe 6, which pipes are continued above ground into the tower 2. The cylinders 3 and 4 are each provided with an upper head 7 and a lower head 8, the upper head being removable for access to the interior of the cylinder and the lower head being provided with an externally threaded neck 9 carrying a packing gland 10. Screwed into the head 7 is a check valve structure 11 which may be of ordinary construction and hence needs no particular description.

Entering the cylinder through the neck 9 of the lower head 8 is a pipe 12 surrounded by the packing gland 10 so that the cylinder may move along the pipe without leakage under conditions of use, the outer surface of the pipe being suitably machined to prevent wear of the packing material. The upper end of each pipe 12 is provided with a valve 13, which may be a ball valve, and the valve is maintained in place but is given sufficient play by a cage 14 which may be screwed or otherwise secured to the upper end of the pipe 12 within the cylinder. The check valve 11 may also contain a ball valve 15, but it is quite feasible to substitute flat valves for the ball valves. It is only necessary that the valve be of suitable type for the purposes of the invention and ball and flat valves are both readily obtainable on the market and either type may be used.

Each pipe 12 is made fast to a support 16 situated in the well casing so as to be below the cylinders 3 and 4, and these cylinders may be so located as to be immersed in the liquid in the well. The pipes 12 may be screwed into the supports 16 and there secured by lock nuts 17. The pipes 12 extend below the support and are there coupled by elbows 18 and a T coupling 19 or otherwise, to a drop pipe, not shown, or the T coupling 19 may constitute an entrance means of liquid into the pipes 12, which latter form stationary displacement pistons for the cylinders 3 and 4.

The support 16 is carried by rods 20, of

which but one is shown, and these rods are continued into the tower 2 and secured to a cross-piece 21 thereof. The pipes 5 and 6 are steadied by spreaders 22 secured at intervals to the rods 20 and traversed by the pipes 5 and 6. These pipes also extend through guides 23 carried by the cross-piece 21 or other suitable part of the tower 2. The weight of the pipes 5 and 6 and the cylinders 3 and 4 is carried by rack bars 24, one secured to each pipe 5 and 6 and located in the tower 2 or at any other convenient point. The rack bars mesh with a gear wheel 25 fast on a shaft 25^a having 15 journal supports 25^b on uprights 25^c of the tower so that the pipes 5 and 6 and parts carried thereby and water contained therein are fully supported. Such structures may therefore reciprocate in the direction of 20 their length with the expenditure of a minimum of power and are constrained to move together in opposite directions by means of the rack and gear wheel coupling. The two pipes 5 and 6 extend through guiding 25 boxes 26 in a pan 27 so as to catch water lifted from the well through the pipes 5 and 6 and escape from the outer ends thereof. An outwardly and downwardly projecting shield or flange 26^a tops each pipe 30 5 and 6 to direct the flow from the pipes clear therefrom without running down the outsides of the pipes. Any suitable means may be employed to cause the reciprocation of the cylinders, and in Figure 1 there is 35 shown a pitman 28 fast to the upper end of the pipe 6 to indicate any appropriate driving means for the pipes. The liquid lifted by the pump into the pan 27 finds ready escape therefrom by way of a pipe 29, 40 but this is also to be taken as indicative of any suitable means for the disposal of the pumped liquid.

In order to provide for easy working of the pump the area of the inner face of each 45 head 8 about the pipe 12 is made greater than the area of the outlet through the upper head of the cylinder. Moreover, the capacity of the check valve 13 is made sufficient to give ample flow of liquid from the 50 pipe 12 into the cylinder 3 or 4. The same condition with respect to the freedom of flow of liquid through the check valve 11 is provided so that the pumps may work without retardation of flow from resistance 55 such as might be offered by the valves.

The pipes 12 acting as displacement pistons or plungers are upright plungers open at the top through check valves and freely communicating at the bottom with the liquid 60 in the well. The pumping action is due to the rise and fall of the cylinders 3 and 4 with their check valves 11, and each cylinder balances the companion cylinder so that comparatively little power is needed for 65 pumping.

If it be assumed that the cylinder 3 has completed a stroke, and the cylinder 4 is about to begin a stroke, which stroke is downward, the pipe 6 accompanies the cylinder 4 in the downward direction, and if it 70 be further considered that the pipe 6 is full of water to its upper end, then the cylinder 4 will telescope on the displacement pipe 12, with the result that the valve 13 closes so that for the time being the pipe 12 may be 75 considered as closed at the upper end, or as acting the same as a solid rod. As the cylinder 4 drops, the water therein simply flows down over the top of the displacement piston 12, always in contact with the inner face 80 of the head 8, until ultimately the displacement piston 12 has reached its upper limit within the cylinder 4. When the cylinder 4 is dropping, it counterbalances the cylinder 3, and the same is true of the pipes 5 85 and 6, the area of which pipes in cross section is substantially that of the displacement pipes 12.

So far as the action of the cylinder 4 with respect to the displacement pipe 12 within 90 it, and the pipe 6 rising from it, the result is the same as though the column of water immediately above the pipe 12 and throughout the cylinder 4 was a solid immovable column rising through the cylinder 4 and 95 into the pipe 6 to the top thereof, so that when the cylinder 4 drops both the cylinder 4 and the pipe 6 telescope over the pipe 12 and the flow is down around the same to and upon the head 8. The column of water 100 corresponding in area to the pipe 6 simply overflows the top of the pipe 6 as the latter drops down around the column of water and the upper end of the column of water overflows the top of the pipe 6 without lifting 105 the column of water, whereby but a negligible amount of force is exerted.

What is claimed is:—

1. A pump comprising oppositely reciprocating cylinders, oppositely reciprocating pipes carrying and actuating the cylinders and conducting fluid from the cylinders to a point of overflow, and stationary displacement pistons each individual to and entering a cylinder through the center of the bottom 110 head thereof and communicating with the liquid being pumped, the area of the bottom head of each cylinder within the latter and exterior to and around the piston being as large as the area of the outlet pipe of the 115 respective cylinder, whereby the full weight of the water in the cylinder and pipe acts upon the head on the down stroke.

2. A pump comprising oppositely reciprocating cylinders each with a discharge pipe 125 rising therefrom at its upper end and carrying and actuating the cylinder and also conducting fluid from the cylinder, and a stationary displacement piston for each cylinder and comprising a pipe extending into the 130

cylinder through the center of the bottom head thereof for delivering liquid thereinto, the area of the bottom head of each cylinder within the latter and exterior to and 5 around the piston being as large as the area of the outlet pipe of the cylinder, each displacement piston and outlet pipe of a cylinder having an upwardly opening check valve, the valve of the piston being located 10 at the upper end thereof within the cylinder, whereby the full weight of the water in the cylinder and pipe acts upon the bottom head on the downstroke.

3. A pump comprising a support, means 15 for sustaining the support at a low point in the well, pipes carried by the support and upstanding therefrom and each provided with an upwardly opening check valve at its upper end, with said pipes held stationary 20 and constituting displacement pistons, reciprocatory cylinders each having its lower head pierced at its center by and movable along a respective pipe, outlet pipes each fast to the upper end of one of the cylinders 25 for reciprocating the latter along the first-named pipes and for conducting liquid from the first-named pipes to the top of the well, upwardly opening check valves between the outlet pipes and the cylinders, said outlet 30 pipes, check valves and cylinders being grouped together for reciprocation in opposite directions, rack bars carried by each of the outlet pipes near the top, and a gear wheel meshing with said rack bars.

35 4. A pump comprising a support, means for sustaining the support at a low point in the well, stationary pipes carried by the support on opposite sides of an upright intermediate line and upstanding from the

support, upwardly opening check valves at 40 the upper end of each pipe, reciprocatory cylinders individual to and receiving the upper end of each pipe with its valve and movable along the said pipes, outlet pipes connected to and reciprocating the cylinders 45 and conducting liquid therefrom to the top of the well, and upwardly opening check valves between the outlet pipes and the tops of the cylinders, the lower head of each cylinder which is pierced by the said stationary 50 pipe at its center having an area outside of the stationary pipe greater than the area of the outlet from the cylinder, whereby the full weight of the water in the cylinder acts upon the said head in the downstroke. 55

5. A pump having reciprocatory cylinders with outlet pipes connected to and rising from the cylinders and serving as actuating and discharge pipes, and stationary displacement pistons over which the cylinders telescope, each piston being in spaced concentric relation to the inner wall of the reciprocatory cylinder by a distance defining an area between them as great as that of the outlet pipe, whereby on the downstroke of the 60 pump cylinder the column of water therein participates in such downward movement and acts upon the lower head of the cylinder outside of the stationary piston and thereby counterbalances the other cylinder and the 65 water from the cylinder overflows the upper end of the discharge pipe.

In testimony that I claim the foregoing as my own, I have hereto affixed my signature.
